UNITED STATES PATENT OFFICE.

THOMAS BARONS, OF BOLTON, CANADA, ASSIGNOR OF ONE-HALF TO JOSS WALSHAW, OF SAME PLACE.

DESIGN FOR A JAW MEMBER FOR HOOF-CUTTERS.

SPECIFICATION forming part of Design No. 34,344, dated April 9, 1901.

Application filed September 13, 1900. Serial No. 29,965. Term of patent 7 years.

To all whom it may concern:

Be it known that I, THOMAS BARONS, a subject of the Queen of Great Britain, residing in the village of Bolton, in the county of Peel, 5 in the Province of Ontario, Canada, have invented and produced a new and original Design for a Jaw Member for a Hoof-Cutter, of which the following is a specification, reference being had to the accompanying drawing, forming part thereof.

The accompanying drawing shows the jaw member in side elevation.

As shown herein, the jaw member comprises the main portion A, terminating in a circular 15 end having a transverse opening therein, a circular enlargement E, having an opening there-

through, a curved neck B, surmounted by head D, and tapering part C, projecting beyond the edge of head D.

Having described my invention, what I 20 claim as new, and desire to secure by Letters Patent, is—

The design for a jaw member of a hoof-cutter as herein shown and described.

In testimony whereof I have signed my 25 name to this specification in the presence of two subscribing witnesses.

THOMAS BARONS.

Witnesses:

B. BOYD,
B. DENNISON.
